(57) **CLAIM**

The ornamental design for a reversible sink facade, as shown and described.

DESCRIPTION

FIG. 1 is a front view of a sink showing a facade design at the front of the sink; and,

FIG. 2 is a back view of a sink showing a facade design at the back of the sink.

The broken line portions of the sink are for illustrative purposes only and form no part of the claimed invention.

1 Claim, 2 Drawing Sheets

FIG. 1

FIG. 2
